UNITED STATES PATENT OFFICE.

JOHN H. FOX, OF BOSTON, MASSACHUSETTS.

DEVICE FOR AUTOMATICALLY STOPPING RAILWAY-TRAINS.

SPECIFICATION forming part of Letters Patent No. 507,976, dated October 31, 1893.

Application filed September 30, 1892. Serial No. 447,436. (No model.)

To all whom it may concern:

Be it known that I, JOHN H. FOX, of Boston, in the county of Suffolk and Commonwealth of Massachusetts, have invented certain new and useful Improvements in Devices for Automatically Stopping Railway-Trains, of which the following description is a specification.

My invention relates to that class of devices by which the steam, air, or vacuum brakes upon a railway train are automatically operated, irrespective of any act on the part of the engineer or other person, either upon or off the train, and consists in so connecting the valve-operating devices, such, for instance, as that described in my Patent No. 457,313, dated August 4, 1891, and which is set beside the track, with a series of levers placed at suitable intervals near the rails, and so that the wheels of a passing engine or car will bear upon them, and the said valve-operating devices will be set or withdrawn by the movement of said levers.

By my simple mechanical improvements nothing is left dependent upon the train operatives, and even a "wild engine" when once properly equipped, will be prevented from running into a preceding train, particularly when it is stopping at a station, or in fact, a train at any location, such as a tunnel or bridge or a curve in the track, where my safety devices may have been placed.

In the drawings accompanying this specification I have illustrated the application of my improvements in the simplest form, where-

in—

Figure 1, is a side elevation, and Fig. 2, is a plan view.

Referring to the drawings by designating letters A is the lever beside the rail, which when depressed by the wheels of a passing train, will set the brake-valve operating-arm C, in the vertical position shown, where it will act upon the brake-valve of any properly equipped train which may pass that location. The lever A, is pivoted at i, in bearings k, and its lower end, a, or that opposite to the one on which the car wheels bear, extends beneath an arm b, upon a shaft c, which also has a slotted arm d, attached to it. The arm C, is also attached to a shaft g, supported in bearings h, and which has a slotted arm f,

secured to it. A rod e, extends from the arm f, to arm d, and is caused to engage therewith by a pin extending from the rod through the slot in each arm. It will be seen therefore, that when the upper end of the lever A is depressed by a passing locomotive or car, its lower end a, will be raised and with it the arm b; this will turn the shaft c, and the arm d, in the direction indicated by the arrow, to the position shown. The connection between the arms d, and f, by means of the rod e, will cause the arm f to move with d, and thus turn the shaft g, and set the arm C into the vertical position shown, ready to operate the brake-valve of a passing train. For the purpose of holding the arm C in this operative position while the train is at a station or while it is passing a certain section of track which the said arm C is intended to protect, the rod e, is extended the required distance along the track, where a latch-lever w is pivoted at n. This lever may be weighted at its inner end, as at w, or operated by a spring m at its outer end. The lever w, may extend between two rod guides p, and engage with a groove in the rod e, or a projection therefrom, whenever the said rod is pushed into the position illustrated. As the train leaves the protected section or location it is desirable to withdraw the arm C, from its operative position, and for this purpose a trip-lever B, is pivoted at o, beside the rail near the latch-lever w, and with its lower end beneath the inner end of the lever w. Thus when the wheels of the passing train depress the upper end of the trip B, its lower end will raise the inner end of the lever w, and release its outer end from the rod e. Immediately the spring l, by its pressure upon the collar u, will push the rod e back, and thereby turn the arm f, and lower the arm C to the position indicated by dotted lines, Fig. 1. Instead of using the spring l, to push back the rod e, a shaft with levers or arms like b, c, d, may be employed with the trip-lever B, it being so constructed as to disengage the latch-lever w, from the rod e, before it turns its shaft c.

The supports for the levers A, B, C, and their connected parts may be secured upon sleepers T. The brake-valve operating arm illustrated, is like that shown in my patent

above-named, the two parts being held in a straight line by springs *s*, *s*.

When using these safety devices with a single track road the rod *e* may be extended beyond the location of the trip-lever *B* the requisite distance and connected with another valve-operating arm *C*, so that both will be set at the same time and thus prevent the approach of a second train from either direction, and the arms *C* may be operated by trains moving in either direction by placing a tripping lever near each and connecting both trips with one locking device. The same devices may be employed at the crossing of two railroads, to prevent a train upon one road from approaching the crossing while a train upon the other is passing over it. This may readily be done as will be well understood by connecting the portions of the rod *e* which may run at right angles to one another by means of a bell-crank, for instance.

My invention is to be distinguished from the variety of devices and mechanical arrangements for setting danger signals, as an illustration such as that shown in the Bodley patent No. 186,531, dated January 23, 1877; for as heretofore stated none of these arrangements accomplished the desired result, of making the safety of each train independent of human vigilance, and my construction is also a simplification and improvement over the electrically operated devices such as described in Patent No. 250,173, granted to W. C. Shaffer November 29, 1881.

When locomotives or cars are provided with devices for opening the brake-valves, such as contemplated in my patent above-mentioned, the use of the safety devices described and shown in this specification will render each train automatically self protecting, when at stations or when upon any portion of the track provided with my said safety devices, and upon roads where the traffic is large it may be used as an absolute and positive block-system to prevent any train from

approaching nearer to another than the distance between two valve operating arms such as *C*, and at far less expense than by the use of any of the systems now employed for such purposes. My present invention is also to be distinguished from the arrangement of mechanical devices described in my said Patent No. 457,313, in which the brake-valve-operating device is indirectly set by the person opening a switch or drawbridge and must be entirely independent of my train protecting devices which are automatically operated by the movement of the train itself.

I do not claim broadly the arrangement of mechanical devices such as shown in said Bodley patent; but

I claim—

In a railway automatic safety block system, the combination with the brake-valve lever of a passing train, of one or more brake-valve operating devices, each secured to a crank-lever supported beside the track; two or more tilting levers as *A*, *B*, beside the rail, one or more of which engages with a crank lever also supported beside the track and one of which engages with a locking device, as *w*; a rod which extends from the valve-operating device to the locking device, and is connected with the respective crank levers, and which is adapted to be engaged by the said locking device, and one or more springs to act upon said rod when disengaged, substantially as described; whereby the pressure of the wheels of a passing train upon one of said tilting levers will place the valve-operating device in a position to operate the brake-valve, and upon the other of said tilting levers to disengage the locking device from said rod, and withdraw said valve-operating device, for the purpose described.

JOHN H. FOX.
